UNITED STATES PATENT OFFICE.

JOHN H. TRESIDER, OF CHISHOLM, AND CLARENCE M. BOSS, OF DULUTH, MINNESOTA.

SAFETY DEVICE FOR REVOLVING PLATFORMS.

Application filed July 17, 1925. Serial No. 44,411.

To all whom it may concern:

Be it known that we, JOHN H. TRESIDER and CLARENCE M. Boss, citizens of the United States, residents, respectively, of 5 Chisholm, in the county of St. Louis and State of Minnesota, and of Duluth, in the county of St. Louis and State of Minnesota, have jointly invented certain new and useful Improvements in Safety Devices for Revolving Platforms, of which the following is a specification.

This invention relates to a new and improved safety device for revolving platforms and more particularly, to a guard 15 arrangement automatically moving with a movable platform to enclose the danger zone of such movement. With types of apparatus, such as steam shovels, locomotive cranes or the like, which include a rotating 20 platform supported upon a fixed platform, there is danger to personnel working about the apparatus when the revolving platform is rotated during its operation. At certain points of its swinging movement the platform 25 will form an acute angle with the fixed platform and persons caught in such angles may be seriously injured.

It is an object of the present invention to provide a new and improved device adapted 30 to define the danger zone in movement of platforms and to thereby warn personnel of danger.

It is an additional object to provide a construction of this character which is 35 simple in design and construction and which may be added to existing apparatus without alteration therein.

Other and further objects will appear as 40 the description proceeds.

We have illustrated our invention somewhat diagrammatically in the accompanying drawings, in which—

Figure 1 is a plan view showing the device applied to a car;

Figure 2 is a side elevation of Figure 1, and

Figure 3 is an end elevation of Figure 1.

The apparatus to which our invention is applied comprises the car or fixed platform

50 11 supported on the wheels 12. The movable platform 13 is pivotally supported on the fixed platform 11 and adapted to swing about a pivot 14. This swinging platform may support a steam shovel, or crane, or any type of apparatus and may be rotated by any form of mechanism. These details

form no part of the present invention and have not been shown.

The guard cables 15 pass around the pulleys 16 located at the corners of the fixed platform and pass over the pulleys 17 into the guide tubes 18. Each end of the cable is provided with a weight 19 freely movable in a guide tube 18. The rollers 20 extend from the lower face of the movable 65 platform 13 and into the path of the cables 15.

When the movable platform 13 is swung to either side, the corresponding roller 20 engages the adjacent cable 15 and swings 70 it out as clearly shown in broken lines in Figure 1. This movement of the cable is permitted by the lengths of the ends of the cable extending into the guide tubes 18. Ex- 75 cess length of cable is had such that the revolving platform may be completely rotated without pulling the weights 19 out of the guide tubes 18. The weights 19 are sufficient to take up any slack and will retain the cable taut as indicated in Figure 1. 80

These guard cables serve to clearly indicate to personnel working about the apparatus the danger zone as the revolving platform swings and will prevent men from being caught between the movable and fixed 85 platforms.

We have shown one preferred form by way of illustration, but we contemplate such changes and modifications as come within the spirit and scope of the accompanying 90 claims.

We claim:

1. In a safety device for movable platforms, a fixed platform, a guard member carried by the fixed platform, and means 95 carried by the movable platform and adapted to engage the guard member when the movable platform extends beyond the fixed platform.

2. In a safety device for movable platforms, a fixed platform, a flexible guard member carried by the fixed platform, and rollers carried by the movable platform and adapted to engage the guard member when the movable platform extends beyond the 105 fixed platform.

3. In a safety device for movable platforms, a fixed platform, a guard cable carried by the fixed platform, under yielding tension, and means carried by the movable 110 platform and adapted to engage the guard cable and extend it beyond the fixed plat-

form when the movable platform extends beyond the fixed platform.

4. In a safety device for movable platforms, a fixed platform, a guard cable passing about pulleys on the fixed platform, weights secured to the ends of the cable to put it under tension and means carried by the movable platform and adapted to engage the guard cable and extend it beyond the fixed platform when the movable platform extends beyond the fixed platform.

5. In a safety device for movable platforms, a fixed platform, a guard cable pass-

ing about pulleys on the fixed platform, weights secured to the ends of the cable to 15 put it under tension, vertical guide tubes housing said weights, and means carried by the movable platform and adapted to engage the guard cable and extend it beyond the fixed platform when the movable platform extends beyond the fixed platform. 20

Signed at Hibbing, Minnesota, this 30th day of June, 1925.

JOHN H. TRESIDER.
CLARENCE M. BOSS.
